Des. 141,146

RADIANT CONVECTOR BASEBOARD PANEL OR THE LIKE

Filed Sept. 13, 1944

Inventor:
John P. Magos.

By Joseph O. Lange, Atty.

UNITED STATES PATENT OFFICE

141,146

DESIGN FOR A RADIANT CONVECTOR BASE- BOARD PANEL OR THE LIKE

John P. Magos, Wilmette, Ill., assignor to Crane
Co., Chicago, Ill., a corporation of Illinois

Application September 13, 1944, Serial No. 115,291

Term of patent 14 years

(Cl. D81—21)

To all whom it may concern:

Be it known that I, John P. Magos, a citizen
of the United States, residing in the county of
Cook, village of Wilmette, State of Illinois, have
invented a new, original, and ornamental Design
for a Radiant Convector Baseboard Panel or the
like, of which the following is a specification,
reference being had to the accompanying drawing,
forming part thereof.

Fig. 1 is a front perspective view of a radiant
convector baseboard panel or the like embodying
my new design.

Fig. 2 is a rear perspective view of the same.

I claim:

The ornamental design for a radiant convector
baseboard panel or the like, substantially as
shown.

JOHN P. MAGOS.
